UNITED STATES PATENT OFFICE.

JOHN R. MITCHELL, OF MONTCLAIR, NEW JERSEY.

THREAD GUIDE.

Application filed September 1, 1922. Serial No. 585,770.

To all whom it may concern:

Be it known that I, JOHN R. MITCHELL, a citizen of the United States, and residing at Montclair, Essex County, New Jersey, 5 have invented certain new and useful Improvements in Thread Guides, of which the following is a specification.

This invention relates to thread guides adapted for use in machines for winding 10 and spooling of that type which is ordinarily made of porcelain and has a slot therein to receive and guide the thread and which is 15 adapted to be mounted on the thread guide rail and to be secured thereto by well known means. It is intended and adapted by its novel features of construction and arrangement of parts to greatly lessen the objectionable wear due to localized friction of the thread thereby greatly prolonging the 20 length of time during which it will perform its function satisfactorily beyond that of the guides now in use and which will at the same time have materially greater efficiency in delivering the thread uniformly and as 25 desired for the best and most satisfactory results. One important and novel feature is that the supporting wear surface for the thread passing through it is materially in advance of the narrow vertical guide slot on 30 the line of movement of the thread, is much wider than the slot and the lower end of the slot is so far below the level of the supporting wear surface that the thread will not make contact with it in travelling 35 through the guide. The greater area of the supporting wear surface and the fact that the entering thread continually varies in its angle of entrance horizontally, thus distributing the wear with substantial uniformity over the surface reduces the wear 40 very much and greatly prolongs the useful life of the guide. Another novel and very advantageous feature is that the narrow slot with vertical sides is formed in 45 a portion projecting from the main body of the guide in the delivery side and is thus materially nearer to the bobbin than in forms now in common use and this shortening of the section of thread between the 50 guide slot and bobbin reduces the swing and lost motion at the end of the travis. It is, of course, necessary for accuracy in delivery that the walls of the slot at the delivery side shall be close together forming a narrow slot and this feature is retained in the

present invention. The novel features will be more fully understood from the following description and claims taken with the accompanying drawings.

In the drawings:

Fig. 1 is a perspective view of a guide embodying the invention showing a section of thread passing through it;

Fig. 2 is a central vertical transverse section of the device at the slot; and

Fig. 3 is a central vertical longitudinal section through the device.

In the embodiment of the invention shown for purposes of illustration there is an elongated body portion 10 having the main portions of its sides inclined symmetrically towards each other from the bottom to the top and its upper surface slightly inclined downwardly from the ends to the central transverse thread slot 11. The bottom of the body portion 10 is formed with a longitudinal depression 12 V-shaped in section so as to adapt it to fit the upper V-shaped surface of the thread guide carrying rail 13 shown in dotted lines in Fig. 80 2. The end portions of the top of the guide have small longitudinal depressions 14 and 15 V-shaped in section adapted to receive well known means, not shown, for securing it to the rail 13.

The central transverse thread slot 11 has vertical side walls spaced apart a material distance on the side where the thread enters but inclined towards each other from that side transversely of the main body 10 whereby the groove is substantially V-shaped in horizontal section. A comparatively narrow vertically extending integral projecting portion 17 is formed in central position on the side of the body 10 from which the thread discharges and the thread slot 11 extends through it having the closely adjacent parallel vertical side walls 18 and 19 and a bottom wall 20 forming the vertical narrow guide slot 21 at their outer ends. The walls 18 and 19 are of the same height as the main body 10 and taper in thickness outwardly having end surfaces in a plane slightly inclined towards the body 10 from the lower edge to the top spaced outwardly a short distance from the lower edge of the discharge side of the body 10 and spaced outwardly a materially greater distance from its upper edge.

The bottom of the slot 11 is compara-

tively wide at the end where the thread enters and is on a curve in substantially the arc of a circle from that edge to a line 22 slightly beyond a vertical plane through 5 the point of the V-shaped depression 12 in the base of member 10 and from that line the portion 23 extends at an angle downwardly to the end portion 24 between the outer edges of walls 18 and 19 which 10 curves downwardly on an arc of small radius. The bottom of the slot at its highest portion where the thread 25 rests is preferably about a quarter of an inch wide and its discharge end at 20 is so much lower 15 that the thread in normal use does not make contact with it.

In prior thread guides of this general type the arrangement of parts has been such that most of the travel of the thread was at 20 the bottom of the narrow portion of the slot with very little chance for movement up and down in the slot and thus the wear due to the friction of the thread was localized and the varying lateral angles at which the 25 thread leaves the narrow slot caused such friction and wear continually on the sides of the narrow portion at its bottom as to soon wear away the material and in effect so enlarge the guide slot that it ceased to deliver the thread with that accuracy in satisfactory work and the guide as a whole had to be discarded and a new one substituted. In the guide constituting the present invention the thread has free up and down 30 movement in the narrow delivery slot and thus the side wear is so distributed longitudinally of the slot as to prolong its effective utility many times. The width of the bottom supporting surface over which 40 the thread moves laterally in addition to its longitudinal movement and the rounded form of that surface so distribute the wear as to permit prolonged use before it becomes noticeable.

45 Although a specific embodiment of the invention is shown for purposes of illustration, it will be understood that it is not limited to that specific form beyond what is indicated in the following claims.

50 Having thus described the invention what is claimed as new and desired to be secured by Letters Patent is:

1. As an article of manufacture a thread guide consisting of a continuous block having a transverse guide slot with vertical sides tapering from the entrance side to the discharge side terminating close together forming a narrow discharge portion the 55 central portion of the bottom of said slot in the line of movement being materially above the portion at the discharge end.

2. As an article of manufacture a thread guide consisting of a continuous block having a transverse guide slot with vertical 60 sides tapering from the entrance side to the

discharge side terminating close together having a narrow discharge portion the bottom of said slot from the leading edge being curved upwardly to the central vertical plane of the block and from that point 70 on to the discharge end being inclined downwardly at such angle that the thread being delivered will not bear on it at or near the narrow discharge portion of the slot.

3. As an article of manufacture a thread 75 guide consisting of a continuous block having a transverse guide slot therein terminating at the discharge end as a narrow slot in a surface of said block slightly inclined to a vertical plane and extending vertically from 80 the top of said block nearly to the bottom plane thereof, the bottom of said guide slot from said discharge end inwardly being inclined upwardly for more than half its length and to a height more than half of 85 that of the block.

4. A thread guide consisting of a continuous block having a transverse guide slot terminating at the discharge end in a narrow vertical slot outlet extending from the 90 top to approximately the bottom and a bottom portion of said slot at a point beyond the central point on the line of movement of the thread which is wide enough to support and permit material lateral movement of 95 the thread distributing wear and which is high enough above the discharge end of the bottom of the slot that the thread may move up and down in the narrow slot of the guide distributing the lateral wear due to friction. 100

5. A thread guide consisting of a symmetrical and continuous block having a central lateral projection on the discharge side extending from its upper edge to its lower edge and having a transverse guide slot 105 which extends through said lateral extension forming a vertical narrow discharge end of the guide slot and bringing it materially nearer to the article receiving the thread than is done with the usual continuous guide blocks heretofore used.

6. A thread guide consisting of a continuous block having a transverse guide slot with a bottom wall portion in advance of the longitudinal center of said slot for supporting the thread being delivered the said portion having a width substantially as great as one-fourth inch and said slot terminating a material distance from the vertical central plane of said block on the discharge side between two vertical wall surfaces close together forming an elongated vertical delivery slot in which the thread may move vertically as well as longitudinally. 115

7. A thread guide consisting of a symmetrical and continuous block having a central lateral projection on the discharge side extending from its upper edge to its lower edge and having a transverse guide slot 125 which extends through said lateral extension 130

forming a vertical narrow discharge end of the guide slot, the side walls of said slot being inclined towards each other from its receiving end approximately to its discharge end and the bottom wall of the slot being on substantially the arc of a circle from the leading edge to and slightly beyond the longitudinal center plane of the block and the bottom from that point on to the discharge end being at a sharp incline downward. In testimony whereof I hereunto affix my signature.

JOHN R. MITCHELL.
